DESIGN FOR AN AUTOMOBILE

Richard C. Johnson, Connersville, Ind., assignor to Auburn Automobile Company, Auburn, Ind., a corporation of Indiana

Application March 27, 1939, Serial No. 83,855

Term of patent 7 years

To all whom it may concern:

Be it known that I, Richard C. Johnson, a citizen of the United States, residing at Connersville, in the county of Fayette and State of Indiana, have invented a new, original, and ornamental Design for an Automobile, of which the following is a specification, reference being had to the accompanying drawing, forming a part thereof.

Figure 1 of the drawing is a side elevational view of an automobile showing my new design; and Figures 2 and 3 are front and rear perspective views respectively.

The characteristic features of my new automobile design are shown in full lines in the drawing.

I claim:

The ornamental design for an automobile, as shown and described.

RICHARD C. JOHNSON.
